UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,770, dated October 31, 1899.

Application filed October 5, 1899. Serial No. 732,726. Term of patent 14 years.

To all whom it may concern:

Be it known that I, JEREMIAH A. SCRIVEN, a citizen of the United States, residing in the city, county, and State of New York, (post-office address No. 18 East Fifteenth street,) have invented and produced a new and original Design for Bifurcated Nether Garments, of which the following is a specification.

The characteristic feature of my design consists in an elongated insertion or panel let into the front of each leg portion or tubular member of a bifurcated nether garment, each of which panels extends from substantially the upper end of the garment to substantially the lower end of each tubular member, each panel being extended laterally to its greatest length at substantially the knee portion of its respective tubular member.

In the drawing the figure represents a front view of a nether garment embodying my design.

In the drawing, A indicates the body por-

tion of a nether garment, from which extend tubular members or leg portions B. Let into the front of the garment are elongated insertions C, each of which extends from substantially the upper end of the garment through the body portion thereof and throughout a tubular member to substantially the lower end thereof. The insertions or panels C are 25 each centrally located in the front of a tubular member, and each panel is extended laterally to its greatest width at the knee portion of a tubular member, as indicated at a. The ribs or wales b of each insertion extend 30 longitudinally throughout the length thereof.

What I claim is—

The design for a bifurcated nether garment, substantially as herein shown and described.

JEREMIAH A. SCRIVEN.
